UNITED STATES PATENT OFFICE.

RICHARD M. WATSON, OF DETROIT, MICHIGAN.

LOOSE-LEAF BINDER.

Application filed July 11, 1927. Serial No. 204,736.

This invention relates to loose leaf binders and has to do particularly with the provision of a novel inexpensive one-piece base or shell structure.

Hitherto in the manufacture of loose leaf binders manufacturers have been constantly directing their attention to the provision of binders which will be inexpensive and simple in manufacture and yet be efficient and 10 present an attractive appearance. One of the main elements of loose leaf binders which has been a great source of experimentation and trouble is the metallic base or shell structure and the manner of securing the same to 15 the back. It has been the common practice to provide the base member or shell with a slight extension at each end punched to receive a suitable rivet, the rivet being forced through the punched hole and expanded. 20 However, this expanded part of the rivet is usually very rough, presents an unattractive appearance and in binders of the cheaper sort this rivet becomes rusty long before the binder is sold. Attempts have been made to 25 overcome the objections to these rivets by providing separate shields for each end of the base member for covering up the rivets.

It is the object of the present invention to provide an extremely simple and inexpensive base or shell member which is made of a 30 single piece of metal and stamped whereby to permit securing of the same to the binder by rivets while at the same time obscuring the general view of the rivets. More specifically, this novel base or shell member is 35 formed of a flat piece of stock, having two holes of relatively different diameters punched at each end, each end of the piece of stock including a single punched hole being 40 bent downwardly and inwardly whereby the holes at each end will register with and be positioned beneath another set of holes in the base. The punched holes in the inwardly bent ends are preferably smaller than the 45 registering holes in the top of the base or shell whereby suitable rivets may be projected upwardly through the bottom holes and the ends of the rivets bent over and riveted into place by any suitable tool inserted 50 through the larger hole from above. Other novel features of this device will be apparent from the drawings and the claims appended hereto.

In the drawings:

Fig. 1 is a plan view of a loose leaf binder

having a base member or shell constructed in accordance with my invention.

Fig. 2 is a bottom plan view of the base member or shell completely assembled ready to be inserted upon the back of the binder. 60

Fig. 3 is a plan view of the flat stock illustrating the manner of fabricating and punching the same preparatory to assembly.

Fig. 4 is a section taken on line 4—4 of Fig. 1 and illustrating the compactness of 65 the completed assembly.

Fig. 5 is a perspective view of one end of the base member or shell illustrating the manner of giving the curvature to the top part of the shell and turning in the longitudinal edges as well as the manner of turning in the ends of the shell whereby to bring the end apertures in alignment. 70

Fig. 6 is a longitudinal section taken on line 6—6 of Fig. 1 and illustrating the preferred manner of securing the base member or shell to the back of the binder. 75

My novel base member or shell may best be described by setting forth the method of manufacture and assembly. This base member may be designated 1 and, as shown in Fig. 3, initially comprises a flat or slightly concave piece of stock having suitable flat end members 2 and 3. This piece of stock is preferably punched, as at 3 and 4, to provide apertures for receiving the ring members, and is preferably punched, as at 5, to provide relatively large apertures adjacent the ends of the main part of the stock. 80

The two end members 2 and 3 are also 85 punched, as at 6, whereby to provide apertures smaller in diameter than the apertures 5 and preferably of just the right size to receive the shanks of suitable tubular rivets or eyelets. 90

In assembling the base member the entire longitudinal central part of the base member, and preferably that part between the apertures 3 and 4, is given a concave curvature, as shown at 7 in Fig. 5. The purpose 100 of this curvature is to permit the operation of suitable shaft members 8 and 9 for connecting the rings which may be designated 10. The edges 11 and 12 of the base member may then be bent around the longitudinal 105 portions of the shaft members 8 and 9, as clearly shown in Figs. 2 and 4. The edges 11 and 12 are adapted to be bent over so as to contact with the shaft members 8 and 9 when the halves of the ring members are 110

together, as shown in Fig. 4. When in this position the two interengaging parts of the shaft members, designated 13, meet at an angle below the plane defined by the supported parts of the shaft members 8 and 9, as shown in Fig. 4. When it is desired to open the ring members 10 it will be obvious that the shaft members 8 and 9 will only have to be forced past the common center and up into the curved part of the base member. It will thus be obvious that by forcing the interconnected parts 13 of the shaft members up and down past the normal center of the bearings thereof that the ring members will be positively held opened or closed.

After the edges 11 and 12 have been bent over, as shown, the end members 2 and 3 may then be bent inwardly in a plane parallel with the general plane of the base member, as shown in Figs. 5 and 6. When so bent inwardly, the apertures 6 are brought into alignment with the larger apertures 5, and when this has been accomplished the base member is ready to be assembled in the back 14 of the binder. The base member may be placed against the back member 14 and suitable rivets 15 forced through the back member 14 and into the lower apertures 6. A suitable riveting tool 16 may then be forced downwardly through the apertures 5 whereby to expand or secure the rivet or eyelet firmly in place.

It will thus be obvious that by providing one aperture for receiving the tubular rivet, and the larger aperture above the same for permitting the insertion of a proper tool to expand or drive home the rivet, that I have provided very inexpensive and compact means for quickly permitting assembly of the base member with the binder, and which at the same time will substantially cover up the ragged edges of the rivet to present an attractive base member as well as to prevent any positive contact between the jagged or ragged rivets and ends. The base member is formed all of one piece, all the holes may be punched out simultaneously and the ends and sides bent over whereby to form a base member which will be as practical and inexpensive to manufacture as the ordinary base members now in use. Furthermore, the base member is all of one piece and preferably extends the full length of the back member and covers whereby the loose leafs will lie flat against the same and thus prevent breaking or creasing of the pages.

What I claim is:

1. A loose leaf binder, comprising in combination a back member, a one-piece metallic base member having a smooth flat portion which extends the length of the back member, the ends of said base member being bent inwardly and parallel with the top part of

the base member, said base member being secured to said back member by means of rivets connecting the bent in portions with the back member.

2. A loose leaf binder comprising in combination a back member, a base member, means at each end of said base member extending underneath and substantially parallel with the top part of the base member, said base member being secured to said back member by securing the underneath extending means directly to the back member.

3. A base member for a loose leaf binder, comprising in combination a strip of metal apertured to receive suitable ring members, the ends of said strip of metal being bent inwardly and parallel to the main strip, the inwardly bent ends and the main strip being provided with registering apertures one larger than the other, the smaller aperture adapted to receive securing devices, and the larger aperture adapted to receive a tool for clamping the securing devices.

4. A loose leaf binder, comprising in combination a folder and an interconnecting back member therefor, a metallic flat surfaced member extending the length of said back member, the ends of said base member being turned inwardly and substantially parallel with the flat surface of said base member, the ends of said flat surfaced base member and said inturned members being provided with registering apertures, the apertures of the inturned members being adapted to receive suitable rivets for securing the base member to the back member, and the other apertures being adapted to receive suitable securing tools.

5. A loose leaf binder comprising in combination a folder and an interconnecting back member therefor, a one-piece base member having the longitudinal edges thereof bent inwardly to receive and provide a substantial hollow compartment for ring members, the ends of the base member being provided with short inwardly extending members bent inwardly on the plane approximately in alignment with the bottom edges of said inturned longitudinal edges, said base member being secured to said back member by fastening means directly connecting said inwardly extending members with the back member.

6. The method of fabricating and assembling base members for loose leaf binders, which comprises forming a single piece of flat blank, simultaneously punching apertures spaced centrally of and in the ends of said blank, inserting ring members at their bearing portions in said centrally spaced apertures, turning in the longitudinal edges to position and form bearings for said ring members, turning in the ends of the blank to cause registration of apertures in the top part of the blank and the inwardly turned part, placing the assembled blank on the

back of a binder, inserting a rivet through the back and through the apertures of the inturned parts of the blank, and then securing the rivets in place by a suitable tool inserted through the registering apertures of the top part of the back member.

7. A loose leaf binder, comprising in combination a back member, a base member comprising a strip of metal extending substan-

tially the length of the member, paper securing means forming a part of the base member, and means positioned underneath of and connected to the ends of the base member, said means being adapted to receive suitable securing means for securing the base member to the back member.

In testimony whereof I affix my signature.
RICHARD M. WATSON.
